POSITION INDICATOR

George Peterson, Jr., St. Davids, Pa., assignor to
 Riverside Metal Company, Riverside, N. J., a
 corporation of New Jersey

Application October 19, 1951, Serial No. 252,157

5 Claims. (Cl. 340—378)

1

This invention relates to electromagnetically operated position indicators which are useful in many situations. One situation which may be mentioned, but only as an example, is to indicate the "up" or "down" position of landing gear of aircraft. More particularly the invention relates to an electromagnetically actuated position indicator wherein circuits remotely opened and closed will cause the position indicator to take one or another extreme position, or normally to occupy a neutral position when neither of the electromagnetic means is energized.

It is an object of the invention to provide an electromagnetically operated position indicator which is rugged, compact and may be economically manufactured and assembled from inexpensive fabricated parts which are, nevertheless, sturdy and reliable in use.

Other objects and advantages of the invention will appear as is described in connection with the accompanying drawings.

In the drawings:

Fig. 1 is a perspective view of a device embodying the invention;

Fig. 2 is a plan view of the device illustrated in Fig. 1 partly broken away to illustrate the interior parts;

Fig. 3 is a longitudinal section view taken along line 3—3 of Fig. 2;

Fig. 4 is a fragmentary detail view illustrating the electromagnetic actuating means in one of its energized positions;

Fig. 5 is a perspective view of the armature;

Fig. 6 is another detail perspective view of the armature of Fig. 5, turned about a vertical axis about 90° from the position illustrated in Fig. 5; and,

Fig. 7 is a schematic diagram of the electrical circuit for the position indicator.

Referring to the drawings, the device is housed in an airtight, cup-shaped, rectangular, box-like casing of metal designated generally by the numeral 10. In one end 10a of the casing is a transparent window 12 through which the position of a movable indicator (designated generally by 39) may be observed. On the opposite end of the casing 10b is mounted a metallic nipple 14 which is externally screw threaded. The nipple may be soldered or otherwise suitably secured to the end of the casing in air-tight fashion. Through the nipple pass three rod-like conductors 16, 17, and 18 having fingers or prongs, such as 16p, 17p, extending outwardly to be engaged by socket members such as 16s and 17s of a conventional plug on the end of a cable to be secured to the nipple by a screw threaded sleeve 15 in conventional fashion. The three conductors 16, 17 and 18 are mutually insulated from one another and spaced apart with their inner ends extending into the casing. Wires are soldered upon the inner ends of the conductors 16, 17 and 18 and are

2

connected to the coils of the electromagnet solenoids as will hereinafter be described.

Preferably all of the operating parts of the device are mounted upon and supported by a U-shaped stamped sheet metal member designated generally by the numeral 19. The parallel arms 19a and 19b (Fig. 2) afford support for the operating parts as will be described in more detail. The transverse portion 19c connecting the arms 19a and 19b is secured to the end wall 10b of the casing so that all of the parts may be mounted upon the end wall and, with the end wall, inserted into the casing as a unit.

Riveted to the side arms 19a and 19b directly opposite each other are two electromagnet solenoids 20 and 40. Since these electromagnet solenoids are identical, only one need be described. Each comprises a spool, such as 22, of molded nylon or other insulation. The axes of the spools are preferably arcuate to receive an arcuate armature arm. A toroidal coil, such as 24, is wound around the spool. One of the leads of the coil 24 is connected to the conductor 16 and one lead of the coil of solenoid 40 is connected to the conductor 18. The other leads of each coil are connected together and to one lead of a resistor R the other lead of the resistor being connected to conductor 17.

The combined armature and indicator assembly is illustrated best in Figs. 5 and 6. It comprises a non-magnetic disc member 30 stamped from thin sheet metal on the opposite sides of which are mounted armatures 32 and 34 which are of substantially Z shape and of identical form.

Members 32 and 34 are stamped from thin sheet metal having magnetic qualities. Each has a short leg, such as 32b, lying upon and secured to the face of the disc 30, but on opposite sides thereof and at diametrically opposite positions.

Each has an arcuate long arm, such as 32a, spaced from but adjacent the periphery of the disc and extending in opposite directions towards each other but, as previously stated, on opposite sides of the disc. The ends of the long arcuate arms 32a and 34a terminate at a distance from each other substantially equal to the length of the spool of the electromagnet solenoid so as to permit the assembly of the combined indicator and armature member by the passage of one of

the arms 32a above and the other 34a below the electromagnet solenoids. Mounted around substantially one-half of the periphery of the disc 30 is a stamped sheet metal indicator member 39 of arcuate form and having a slight transverse curvature which adds some stiffness to the otherwise very flexible sheet metal of which the indicator member is made. Preferably the indicator member is made of non-metallic material.

It is secured to the disc 30 by lugs or tabs 39t bent down to lie upon opposite sides of the surface at diametrically opposite points on the disc 30. These points may be on opposite sides of the disc

from the short arms (e. g. 32b) of the armature members 32 and 34 so that rivets or other securing means may serve the common purpose of attaching both the armature members and the indicator member to the disc 30. Preferably the indicator member has in its central portion an indication of the neutral or "off" position designated generally as 39n and at either end portion an indication of one extreme or the other extreme position, such as "up" and "down" when the device is used for indication of the position of the landing wheels of aircraft.

In order to pivotally mount the combined armature and indicator member, axial pivot pins 36, 36 are located at the center of the disc 30 to be received within bearing bolts 38 screwed into apertures in the ends of the arms 19a and 19b in alignment, the ends of the screws 38 having conventional conical seats for the pivot pins.

In order to maintain the indicator and armature member in normally neutral position where in the portion 39n is opposite the window 12, a coiled helical spring 53 is provided having one end turned laterally into a small anchoring hold perforated in the disc 30 and the other end anchored to one of the arms such as 19b of the frame 19 or to an anchor lug 52 as illustrated in Fig. 2, such anchoring lug being fixedly secured to the arm 19b at adjacent the pivot bearing screw 38.

In order that the indicator-armature unit shall be dynamically and statically balanced a portion 39' of the disc 39 may be stamped out to compensate for the added weight of the armature members.

By reference to Fig. 7 typical circuit connections may be observed wherein the switch 54 closes when the wheels of the aircraft are up causing energization of the solenoid coil 49 through the source of current 57 and resistor R. When the wheels are lowered, the switch 56 is closed and the switch 54 opens thus causing energization of the coil 20 in a similar fashion. When neither of the switches is energized the centering spring 50 will cause the armature to take a neutral or "off" position as illustrated in Fig. 3. Upon energization of either coil, the armature (see Fig. 4) will enter into its coil causing rotation of the armature-indicator member and moving the indicator to show either the up or the down signal indication and thus advise the observer of the existing condition.

Since the disc 30 is non-magnetic as well as the indicator member 39 and since the solenoid coils 20 and 49 are separated and have the disc 30 between them the coils are entirely separate so that the electromagnetic paths of the two solenoids and their armatures are entirely electromagnetically separate and unaffected one by the other.

From the foregoing, it will be observed that my position indicator may be manufactured mainly from stamped sheet metal parts which are relatively thin and inexpensive and may be easily worked and secured together, the lightweight and accurate balancing of the parts making the device very little susceptible to vibration and improper or accidental operation, and thus very reliable in operation under adverse conditions.

While a particular embodiment of the present invention has been illustrated and described herein, it is not intended to limit the invention to such a disclosure and changes and modifications may be incorporated and embodied therein within the scope of the following claims.

I claim:

1. A unitary electromagnetically operated indicating device comprising a frame stamped from non-magnetic sheet metal and having parallel arms, a solenoid coil mounted on the inner surface of each arm in opposite positions with their cores in parallel, a pivoted indicator and armature unit rotatably mounted adjacent the solenoids about an axis parallel thereto and comprising a rotary disc member of non-magnetic material, armature members mounted on opposite sides of said disc member, each having an arcuate arm portion adapted to enter one of said solenoid cores, said arcuate arm portions terminating at a distance substantially equal to the coil length, an indicator member mounted on the periphery of said disc member and moving with the disc member into two energized positions from a neutral center position, and a centering spring anchored to a frame arm and biasing said disc member in central position.

2. A device as claimed in claim 1, wherein the indicator member has tabs at diametrically opposite positions lying on opposite sides of the disc member, said armature members having portions adjacent said tabs but on opposite sides of the disc member, and securing means passing through said tabs and opposite armature portions jointly securing the indicator and armature members to the disc.

3. A device as claimed in claim 1, wherein said disc member moves in a plane between said solenoid coils and affords a magnetic barrier between them adjacent the armature arms.

4. A device as claimed in claim 1, wherein said frame, disc, indicator and armature members are thin sheet metal.

5. An electromagnetically operated indicating device comprising a housing having a window therein, an indicator movable to show a plurality of positions of said indicator through said window, a supporting frame carrying all operating parts of said device, a wall of said housing supporting said frame whereby the frame and wall, as a unit, may be assembled in the housing, said frame having parallel arms, a pair of electromagnetic solenoid coils mounted opposite each other on the inside surfaces of said arms with their cores substantially parallel, an indicator and armature assembly comprising a disc of non-magnetic material, an armature secured on each side of said disc each having an arcuate arm adapted to enter the core of one of said solenoids on energization of the solenoid, means pivotally mounting said armature-indicator assembly between said frame arms with said disc moving in a plane between said solenoids, and a centering spring moving said indicator-armature assembly into a midposition when neither of said solenoids is energized.
